CLAIM

The ornamental design for a display box, as shown and described.

DESCRIPTION

FIG. 1 is a right perspective view of a display box showing our new design.

FIG. 2 is a left perspective view thereof.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof.

FIG. 8 is a bottom plan view thereof.

FIG. 9 is a front perspective view of the display box in an open configuration.

FIG. 10 is a bottom perspective view thereof.

FIG. 11 is a front elevational view thereof.

FIG. 12 is rear elevational view thereof.

FIG. 13 is a right side elevational view thereof.

FIG. 14 is a left side elevational view thereof.

FIG. 15 is a top plan view thereof.

FIG. 16 is a bottom plan view thereof.

FIG. 17 is a right side elevational view of the display box in a slightly partially open configuration.

FIG. 18 is a right side elevational view of the display box in a partially open configuration.

FIG. 19 is a right perspective view of another embodiment of a display box showing our new design.

FIG. 20 is a left perspective view thereof.

FIG. 21 is a front elevational view thereof.

FIG. 22 is a rear elevational view thereof.

FIG. 23 is a right side elevational view thereof.

FIG. 24 is a left side elevational view thereof.

FIG. 25 is a top plan view thereof; and,

FIG. 26 is a bottom plan view thereof.

The uneven length, dashed lines, shown in FIGS. 19-26, represent textural components and form no part of the claimed design. The uniformed dash-dash broken lines shown in FIGS. 1, 2, 5, 6, 7, 19, 20, 23, and 24 of the drawings represent portions of the article that form no part of the claimed design.

1 Claim, 26 Drawing Sheets
